W. E. WINE

CAR DOOR LOCKING DEVICE

Filed Jan. 12, 1922

Fig. 2.

Fig. 1.

Inventor

William E. Wine

Parker Cook,

Attorney

UNITED STATES PATENT OFFICE.

WILLIAM E. WINE, OF TOLEDO, OHIO.

CAR-DOOR-LOCKING DEVICE.

Application filed January 12, 1922. Serial No. 528,653.

My invention relates to new and useful improvements in car door locking devices and has for an object to provide a lock that may be readily and quickly attached to a car having a drop bottom door, which lock is extremely simple in construction, readily assembled and quickly and easily operated.

Still another object of the present invention is to provide a locking device comprising a bracket, on which is a small housing, and in which is mounted a pivotal hook adapted to engage a ledge formed on the door, so that the said hook will hold the door in a closed and supported position; and to further provide a lug on the hook above the pivoted point that is adapted to be held against movement by an arm which is also pivoted to the bracket, and to provide means for holding the arm in locked relation with the lugs formed on the upper end of the hook to thereby tightly lock the hook and the door in their closed positions.

Still another object of the invention is to provide a locking device having but few parts, all of which are contained on a bracket, and to provide a ledge in the form of an angle iron that is to be secured to the bottom of the door and transversely thereof, which ledge will be engaged by the hook of the locking device when the door is in its supported position.

Still another object of the invention is to provide a locking device that is relatively cheap to manufacture, compact in nature, and easily operated.

With these and other objects in view, the invention consists in certain new and novel constructions and combination of parts as will be hereinafter more fully described and pointed out in the claims.

Referring now to the drawings, showing a preferred embodiment of the invention,

Fig. 1 is a view in side elevation showing the side of the door, the door being in its supported and locked position.

Fig. 2 is a sectional view taken on line 2-2 of Fig. 1.

Referring now more specifically to the invention, it will be seen that it comprises a bracket or plate 1, which is provided at several points with bosses 2, which are drilled for the reception of rivets 3 so that the bracket may be rigidly fastened to the side of the car 5. A plate 6 is also shown

in Fig. 2 which may be placed on the inner side of the car body 5 through which some of the rivets may be passed, which plate, of course, strengthens the car side at the point of attachment of the bracket. Also formed on the plate 1 is the integral casing 7 which is open along the upper and lower edges and in which casing is pivotally mounted the hook 8, a countersunk rivet 9 being passed through the upper end of the casing 7 and the bracket 1 for securely pivoting the hook within the casing. On the upper end of this hook 8 and beyond the pivotal point thereof is shown the outstanding lip or lug 10, the function of which will shortly be described. To a point below this lug 10, and to the left thereof (Fig. 1) is formed a boss 11 on which is pivotally mounted a locking arm 12, a pivot 13 forming the pivotal connection, while on the lower end of this arm and below the pivotal point is formed the weighted head 14, so that this arm 12 will normally assume the position as shown in the dotted lines as shown in Fig. 1. A further boss 15 is shown located above the boss 11, on which is pivotally mounted the dog 16, a countersunk rivet 17 forming this pivotal connection, while a strap 18 is passed from the boss 11 to the boss 15 for holding the arm 12 and the dog 16 to the bracket.

In Fig. 1 I have shown the strengthening rib 19 as extending from the bracket 1 to the casing 7, and most of the parts are shown as cored to provide strength and achieve lightness, and it is to be understood that further ribs might be used if found necessary, or, the coring of the metal might be dispensed with.

A side of a door 20 is shown which is hinged at its rear end to a bracket 21, which bracket may be riveted to a center sill (not shown). Secured to the bottom of the door and extending transversely thereof is an angle iron 22 which extends outwardly beyond the free side of the door, this angle having its upper leg extending in a direction to be engaged by the jaw of the hook 8 when the door is in its closed position. In the drawings, I have shown the hook 8 engaging the angle 22 while the arm 12 is in its locked position beneath the lip 10 of the hook and the dog 16 is jammed downwardly to tightly hold the arm 12 in its locked position.

tion. When the locking device is in this position it will be impossible for the hook to become accidentally disengaged from the angle 22, the locking devices therefore supporting and locking the door in its closed position.

To release the door, it will only be necessary to force the dog 16 rearwardly as shown in the dotted lines and the arm 11 will swing 10 to the position also shown in dotted lines, thereby making it possible for the hook 8 to be swung from disengagement with the angle 22, allowing the door to drop. To lock the door, of course, the procedure just 15 mentioned is reversed, the locking and unlocking of the device being but a matter of a moment.

Although I have shown only one side of the door, and one locking device, it is to 20 be understood that in most instances the same arrangement will be applied to the other side of the car so that the door may be supported and locked from its opposite sides.

25 From the foregoing it will be seen that I have provided a locking device which is exceedingly simple in construction, efficient in service and relatively cheap to manufacture.

Many slight changes might be made without 30 in any way departing from the spirit and scope of the invention.

What I claim as new and desire to secure by Letters Patent is:

1. In a car door locking device, a bracket, 35 a hook pivotally mounted on said bracket and an upper portion of said hook projecting beyond the pivotal point, an arm pivotally mounted on said bracket and adapted to be swung into the path of movement of 40 the upper portion of said hook, thereby holding the hook in a locked position, and means for locking the said arm in the said position.

2. A car door locking device, comprising 45 a bracket, a casing on said bracket, said casing being open along its upper and lower edges, a hook pivotally mounted on said bracket and within said casing, a lug formed on the upper end of said hook, an arm pivotally mounted on said bracket adapted to swing into and out of the path of movement of said lug formed on said hook and means for locking the pivotal arm in the path of travel of said lug to thereby lock 50 the hook in its forward and locked position.

3. A locking device for car doors, comprising a bracket, a hook pivotally mounted on said bracket, and a lug formed on the upper end of said hook, an arm pivotally mounted on said bracket and adapted to swing into and out of the path of movement of said lug formed on the upper end of said hook, and means for locking the pivotal arm in engagement with said lug to thereby hold 60 the hook in its forward and locked position.

4. A locking device for car doors comprising a bracket, a casing on said bracket said casing being opened along its upper and lower edges, a hook pivotally mounted on said bracket and within said casing, a lug formed on the upper end of said hook and without said casing, an arm pivotally mounted on said bracket and weighted at its lower end, said arm adapted to swing into and out of the path of movement of 70 said lug formed on said hook and to normally be without the path of movement of said lug, and means for locking the pivotal arm within the path of travel of said lug to thereby lock the hook in its forward 75 position in said casing.

5. In combination with a freight car having a drop bottom door and a ledge extending beyond the free edge of the door and secured thereto, a locking device secured to 80 the side of the car body and above said ledge, said locking device comprising a bracket having a hook pivotally mounted thereon, said hook engaging the ledge on said door when said hook is in its locked 85 position, a lug formed on the upper end of said hook, an arm pivotally mounted on said bracket, the end of the arm adapted to swing into and out of the path of travel of said lug, and means pivoted to the bracket 90 for locking the arm in the path of travel of said lug to thereby hold the hook into engagement with the ledge on said door and tightly hold the door in its locked position.

6. In combination with a car having a drop door, an angle iron secured to the bottom of the door, and extending beyond the free side of the door, a locking device secured to the side of the car body, and above said angle iron, said locking device comprising a bracket, a casing formed on said bracket, a hook pivotally mounted in said casing and adapted to engage the angle iron on said door when said door is in its locked position, a projection formed on the upper 100 end of the hook, means pivotally mounted on the bracket, adapted to swing into and out of the path of travel of the projection of said hook and further means to lock the first mentioned means to thereby lock said hook in engagement with the angle iron on 105 said door.

7. In a door device for railway cars, the combination with a swinging door of a supporting mechanism therefor, the same being 110 affixed to the car body and comprising an outer and an inner plate, a door-securing hook pivoted between the two plates, hook-retaining means overlapping but one of said plates, and means passing through one of the plates only and through a portion of the car for securing the supporting mechanism to the car body.

8. In a door device for railway cars, the combination with a swinging door of a sup- 115

porting mechanism therefor, the same being affixed to the car body and comprising an outer and an inner plate, a door-securing hook pivoted between the two plates, hook-
5 retaining means overlapping but one of said plates, and means passing through one of the plates only and through a portion of the

car for securing the supporting mechanism to the car body, the said supporting mechanism being self contained and applicable to 10 the car body and removable therefrom as a single unit.

In testimony whereof I affix my signature.

WILLIAM E. WINE.
